UNITED STATES PATENT OFFICE.

EDWARD McGOUGH, OF COLUMBUS, OHIO.

FLY-PAPER HOLDER.

Application filed September 29, 1924. Serial No. 740,640.

To all whom it may concern:

Be it known that I, EDWARD McGOUGH, a citizen of the United States, residing at Columbus, in the county of Franklin and 5 State of Ohio, have invented new and useful Improvements in Fly-Paper Holders, of which the following is a specification.

The present invention is directed to improvements in holder for fly-paper of the 10 sticky variety.

The primary object of the invention is to provide a device of this character so constructed that a sheet of fly-paper can be easily and quickly applied to or removed from 15 the holder, and when in place will be held positively against warping and wrinkling.

A further object of the invention is to provide a holder of this nature having associated therewith a guard to prevent persons 20 or objects, such as curtains or draperies coming in contact with the fly-paper, the construction of the guard being such as to permit the flies to readily alight upon the paper.

25 A still further object of the invention is to provide a device of this kind which is extremely simple and consequently can be manufactured at a very small cost.

With these and other objects in view, this 30 invention resides in the novel features of construction, formation, combination and arrangement of parts to be hereinafter more fully described, claimed and illustrated in the accompanying drawings, in which:—

35 Figure 1 is a top plan view of the device.

Figure 2 is a sectional view on line 2—2 of Figure 1.

Figure 3 is a transverse sectional view, the frame being raised to permit the fly-paper to 40 be applied or removed.

The holder comprises a wire frame 1, rectangular in shape and is of such dimension as to confine a sheet of standard size sticky fly-paper 2. The guard consists of a plurality of transversely and longitudinally disposed wire arched bars 3 and 4, the ends thereof being suitably secured, respectively, to the side bars 5 and end bars 6 of the frame 1.

45 To hold the sheet of fly-paper 2 in place a pair of clamps 7 are provided, each clamp consisting of a pair of rods 8 and 9, the for-

mer having their outer ends terminating in coils 10 adapted to pivotally engage the adjacent side bar 5 of the frame, said coils 55 terminating in resilient fingers 11 which overhang said bar for a short distance. The rods 8 and 9 have their inner end provided with eyes 12 and 13, respectively, which are so arranged that the eyes of one rod slidably 60 engage the companion rod to permit the rods 9 to slide relative the rod 8, the purpose of which will appear later.

The outer ends of the rods 9 terminate in resilient fingers 14 and resultant open loops 65 15, the loops being adapted to slidably and detachably engage the adjacent side bar 5 of the frame 1, said finger, like the finger 11, overhangs the bar 9.

A sheet of cardboard 16 or other suitable 70 material is placed upon the rods 8 and 9 with its side edges normally engaged under the fingers 11 and 14, and it is upon this board that the sheet of fly-paper rests with its sticky surface uppermost. It will be ob- 75 vious that the fingers 11 and 14 serve to hold the sheet 2 firmly gripped adjacent its corners owing to their resiliency.

When it is desired to place a sheet of fly-paper in the holder the rods 9 are slid outwardly until the loops 15 disengage the associated side bar 5, whereupon the frame 1 is swung upwardly and the edge of the sheet 2 is slipped under the fingers 11. The frame is then swung downwardly and the rods 9 85 pushed inwardly until the loops 15 engage the adjacent side bar 5 and at which time the fingers 14 yieldably engage the adjacent side edge of the sheet 2. It will be obvious that the fingers 14 not only retain the sheet 90 2 in place, but also serve to hold the frame 1 secured to the clamps 7, whereby the device can be lifted conveniently from place to place upon grasping the bars of the guard and without danger of the hands coming in 95 contact with the fly-paper.

What is claimed is:—

In a fly-paper holder, the combination with a frame including side bars, of clamps 100 consisting of rods having their inner ends slidably connected for longitudinal adjustment, the outer ends of said rods being provided, respectively, with coils and loops, the former being permanently and pivotally

connected to the side bars and the latter being slidably and detachably engaged with said bars to permit disengagement thereof from the said bars, said loops and coils having associated therewith resilient fingers for yieldably engaging a sheet of fly-paper to hold the same within the confines of the

frame, said frame being adapted to swing independently of the clamps when the loops are disengaged from the bars, as and for the purpose set forth.

In testimony whereof I have hereunto set my hand.

EDWARD McGOUGH.
